CONTINUOUS INTERLEAVED RECORD SUPPLIES

Edward Kirby Bottle, deceased, late of Elmira, N. Y., by Sara Jane Bottle, administratrix, Elmira, N. Y., assignor, by mesne assignments, to American Sales Book Company, Inc., a corporation of Delaware

Application December 10, 1931, Serial No. 580,002

1 Claim. (Cl. 282—12)

This invention relates to improvements in means for separating relatively superposed sheets or strips from each other and with reference to some of the more particular features thereof it relates to an improved arrangement for separating carbon or transfer sheets from interleaved transfer position with record sheets adapted for use in various forms of manifolding apparatus such as typewriting machines, autographic registers and the like.

It is a general object of the invention to provide, for manifolding records of the class mentioned, an improved arrangement whereby the carbon or transfer sheets may be readily stripped or separated from interleaved position with the record strips after the manifold inscriptions have been completed.

According to another feature of the invention, record strips of the long continuous traveler type, together with interleaved carbon or transfer strips of a similar type are formed and assembled in an improved manner whereby upon severance of sections or sets of leaves from the assembly the sections of carbon strip can be separated from the sections of record strips very conveniently and without requiring the exercise of skill or great care.

Another object of the invention is to provide an improved record assembly of the class mentioned wherein the sets of record leaves with interleaved transfer sheets, as detached from a long continuous composite record assembly, may be prepared for stripping or separation into different groups without any objectionable mutilation of the record leaves.

Still another object of the invention is to provide a composite record assembly of the class mentioned having an improved arrangement of the superposed long continuous strips whereby tearing of sections or sets of leaves from the assembly is facilitated and the tearing or severance of the strips along predetermined lines assured.

Another object of the invention is to provide an improved arrangement of relatively superposed continuous strips wherein the transverse severance lines of the alternate strips depthwise of the assembly are longitudinally displaced from other severance lines of a group, thus providing for selective gripping of a set of leaves or sheets severed from the assembly along these severance lines. This provides an arrangement whereby the severed group of leaves may readily be separated from each other by means of this selective gripping formation.

Another object of the invention is to provide an improved composite record assembly of the class mentioned which is inexpensively prepared for stripping or separation of the superposed sheets and which is practicable and convenient in use.

Other objects of the invention will be in part pointed out in the following detailed description of certain illustrative but preferred embodiments of the invention and will be in part obvious in connection therewith.

The invention accordingly comprises an article of manufacture possessing the features, properties, and the relation of elements which will be exemplified in the article hereinafter described and the scope of the application of which will be indicated in the claim.

For a more complete understanding of the nature and objects of the invention reference is had to the following detailed description and to the accompanying drawings in which

Fig. 1 is a fragmentary perspective view of a composite record assembly embodying the invention;

Fig. 2 is a plan view of a section of one of the record strips shown in Fig. 1;

Fig. 3 is a plan of a section of one of the carbon or transfer strips;

Fig. 4 is a plan of a composite manifolding assembly embodying a slightly modified form of the invention;

Fig. 5 is a plan of a section of one of the transfer strips used with the assembly of Fig. 4;

Fig. 6 is a plan of a manifolding assembly embodying a further modified form of the invention, and

Fig. 7 shows a section of one of the transfer strips employed with the form of Fig. 6.

Referring to the drawings for a detailed disclosure of the invention it will be observed that record strips 10 of the long continuous traveler type are relatively superposed with each other. Each of the record strips or work webs 10 is provided with a longitudinal series of transversely extending severance lines 11 dividing each strip into a longitudinal series of record leaves or sheets 12. These severance lines may be weakened to facilitate severance of the record strips from the assembly in any approved manner as, for example, perforating the strips along the respective severance lines. Also, each record sheet or leaf thus formed may be provided with a blank form or writing space as indicated at 13. When the continuous record strips thus formed are assembled the transverse severance lines 11

in the several strips are arranged substantially in alignment with each other and this alignment will be maintained throughout the assembly because the longitudinal spacing of the severance lines will be substantially the same in all of the record strips.

Interposed between adjacent record strips 10 are carbon or transfer strips 14 also of the long continuous traveler type and preferably extending for the full length of the record strips. These transfer strips are shown as being coated with carbon or transfer material 15 only on the under surface thereof, this surface being coated with this transfer material throughout its extent in the embodiment shown. However, if desired, portions of the transfer material may be omitted for selective inscription and both upper and lower surfaces may be coated in this manner. Transfer strips used in this manner are ordinarily of the one-time type. In other words, they are ordinarily discarded after the inscription on one set of leaves has been completed.

Each transfer strip 14 is also formed with a longitudinal series of transversely extending severance lines 16 also preferably weakened in any preferred manner. These severance lines 16 are longitudinally spaced the same as the spacing of the severance lines 11, thus dividing each transfer strip into a longitudinal series of transfer sheets 30 or leaves 17. Thus, it will be seen that the composite record assembly including the record and transfer strips will be divided by these severance lines 11 and 16 into a longitudinal series of leaf sets comprising the record leaves, together with 35 the transfer leaves arranged in transfer relation therebetween.

When the transfer strips thus formed are assembled in superposed manifolding relation with each other as shown in Fig. 1, the severance lines 40 11 of the record strips are longitudinally offset or displaced from the adjacent severance lines 16 of the transfer strips. The amount of this displacement may vary but it will be sufficient to provide selective gripping extensions when the 45 leaves are severed along the respective lines as more fully explained below. The severance lines 11 and 16 are thus arranged into a series of groups along the record assembly. The severance lines 11 of each group are substantially in alignment with each other and if more than one transfer strip is employed, the severance lines 16 of each group are also substantially in line with each other. Since the record strips are ordinarily arranged in alternate relation with the transfer 50 strips, the severance lines 11 of each group are aligned with each other in the alternate strips and the lines 16 are also similarly aligned with each other in the alternate strips.

When the record assembly is folded to form a 60 zigzag supply pack 18, the transverse fold lines will usually be coincident with the severance lines 11 of the record strips as shown. This, of course, will necessitate folding of the transfer strips along transverse lines 19 which are longitudinally 65 displaced from the severance lines of the carbon strips. In other words, the folds of the record strips are coincident with the severance lines thereof, but the fold lines of the transfer strip are longitudinally displaced a short distance from the 70 respective severance lines 16 thereof. It will, of course, be understood that the composite record may be disposed otherwise than the zigzag supply pack 18, as for example, in a multiply roll.

In order to start the tearing correctly along the 75 respective severance lines 11 and 16, it is some-

times desirable to provide starter formations at the edges of the strips leading to the respective severance lines. In Figs. 1 and 3 such starter formations are shown in the form of recess or notches 20 at the edges of the transfer strips 14. These starter formations may assume different forms in practice or may be utilized in the record strips as well as the carbon strips if desired. It is preferred, however, to use them only in the transfer strips, thus avoiding mutilation of the record strips. However, a short slit coincident with each severance line 11 and extending all, or substantially all the way through the paper at the strip edge could be utilized in the record strips without mutilation thereof. The carbon strips 15 may also have such slits.

When a set of record leaves 12 has been inscribed in a writing machine, or by other means, the inscribed set of record leaves, together with the interleaved transfer leaves 17, may then be severed from the assembly along the group of severance lines 11 and 16. Correct starting of the tearing along the respective lines is assured by means of the starter recess 20. Complete severance of the leaves is thus effected along the respective severance lines, thus leaving the edges of the record and transfer leaves longitudinally displaced or offset from each other. This provides selective gripping extensions or margins whereby all of the record leaves may be selectively gripped at one side or end of the detached 30 separate leaves and all of the transfer leaves may be similarly selectively gripped at the opposite end of the detached set. In this manner the detached transfer leaves may be very easily separated from the detached record leaves.

It will be noticed that the severance lines extend uninterruptedly across the bodies of the strips either up to the longitudinal edges thereof, or up to the starter formations in case the latter are employed. Also the relative longitudinal displacement between the severance lines 11 and those at 16 of each group is in the same direction at each group of severance lines throughout the length of the record assembly. This arrangement assures clean and unmarred severed edges of the leaves severed from the assembly and provides a record device whereby the selective grip formations are positioned the same in each of the severed sets of leaves.

According to the form of the invention illustrated in Figs. 4 and 5, the general arrangement of record and transfer strips is the same and corresponding parts are designated by the same reference characters with the addition of the index "a". As shown, the long continuous record strips 10a are arranged as above described and one or more continuous transfer strips 14a are interleaved in transfer relation. Both the record and transfer strips are also provided with transverse severance lines 11a and 16a equally longitudinally spaced and arranged in groups as aforescribed. However, in this embodiment no starter notches or formations are used inasmuch as the severance lines 11a and 16a may be made sufficiently weak and fragile, especially at the ends thereof so that correct starting of the tearing operation along the respective lines is assured. This assembly may be folded into a zigzag supply pack or otherwise disposed to form 70 a supply package. Each of the record leaves of one or more of the record strips may also be formed with spaced apertures 21 which may serve to file the record leaves after the inscriptions have been made. It will readily be under-

stood that this form of the invention functions the same as that above described and that the transfer leaves may be separated from the record leaves in the same manner.

5 Referring to Figs. 6 and 7, a similar assembly of record and transfer strips is also shown and the same reference numerals with index "b" are used to designate corresponding parts. The record strips or webs 10b are superposed and aligned 10 with each other and the continuous transfer strip or strips 14b are interleaved in transfer relation therewith. Also, the record and transfer strips are formed as before with transverse severance lines 11b and 16b equally spaced as 15 before and offset longitudinally with reference to each other at each group of severance lines. However, the forward end of each of the record leaves 10b as defined by its respective severance line 11b is spaced forwardly from the corresponding forward end of the transfer leaf 17b 20 as defined by the severance line 16b. This provides that the forward ends of the record leaves just ahead of the adjacent ends of the transfer leaves when the sets of leaves are severed from 25 the assembly. It is clear that either this or the alternate arrangement of Fig. 1 may be utilized; sometimes it is desired that the transfer leaves extend fully up to the forward ends of the record leaves to effect transfer inscription up to the ends of the latter whereupon the form of Fig. 1 will be preferred, but if transfer inscription approximately up to the rear ends of the record leaves is desired, the form of Fig. 6 will be used.

30 Starter formations or notches 20b are provided at one longitudinal edge of each of the transfer strips 14b leading from the strip edge to the respective severance lines 16b. These notches or indentations 20b are formed with curved inner terminals 22 preferably arranged 35 symmetrically with reference to the severance lines. This arrangement for some purposes is

found desirable since it is very effective in starting the tearing correctly along the severance lines and it also affords a little more space to assure selective gripping of the forward ends of the record strips during the performance of the stripping operation. The record assembly as made up in this manner is used similarly to the other embodiments and a detailed description of the 5 operation will be obvious from the foregoing disclosure.

10 Since certain changes may be made in the above article and different embodiments of the invention could be made without departing from the scope thereof, it is intended that all matter contained in the above description or shown in 15 the accompanying drawings shall be interpreted as illustrative and not in a limiting sense.

18 Having described this invention, what is claimed as new and desired to be secured by Letters Patent, is:

20 A manifolding assembly including a plurality of relatively superposed continuous record strips and a continuous transfer strip interleaved in transfer relation therewith, each of said record and transfer strips having a series of longitudinally spaced transverse weakened severance lines, said record strip severance lines dividing 25 said record strips into rectangular record sheets, the longitudinal spacing of said severance lines being substantially the same in the record and transfer strips, and the severance lines of said transfer strip being longitudinally displaced from the respectively adjacent severance lines of the record strips, said severance lines extending uninterruptedly across the bodies of the strips and 30 said transfer strip having starter notches leading from the strip edge to the respective transfer strip severance lines.
